(57) **CLAIM**

The ornamental design for an electric candle, as shown and described.

DESCRIPTION

FIG. 1 is a perspective view of an electric candle in accordance with a first embodiment showing a switch in dotted lines;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof;

FIG. 8 is a perspective view of an electric candle in accordance with a second embodiment showing the switch and imitation wax in dotted lines;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top view thereof; and,

FIG. 14 is a bottom view thereof.

The broken lines shown in the drawings are included for the purpose of illustrating portions of the electric candle and form no part of the claimed design.

1 Claim, 8 Drawing Sheets
